HALSEY G. KINDER, OF CHICAGO, ILLINOIS, ASSIGNOR TO W. W. KIMBALL COMPANY, OF CHICAGO, ILLINOIS, A CORPORATION OF ILLINOIS.

MEANS FOR CONTROLLING ADJUSTABLE COMBINATION STOP-ACTIONS IN SELF-PLAYING ORGANS.

1,101,937.

Specification of Letters Patent. Patented June 30, 1914.

Application filed February 5, 1912. Serial No. 675,840.

To all whom it may concern:

Be it known that I, HALSEY G. KINDER, a citizen of the United States, residing at Chicago, in the county of Cook and State 5 of Illinois, have invented certain new and useful Improvements in Means for Controlling Adjustable Combination Stop-Actions in Self-Playing Organs, of which the following is a specification.

10 This invention relates to the art of self-playing organs, and has reference more particularly to automatic means for controlling the stop actions of such instruments. Self-playing organs wherein the individual 15 stops or fixed combinations thereof are thrown into and out of action by pneumatic motors controlled from the tracker range and perforated music-sheet are known. Many organs are equipped with mechanisms 20 known as adjustable combination stop actions whereby adjustable combinations of stops may be set in advance of the playing of a piece of music, and may be successively brought into action at the required 25 times through the agency of a manually operated controlling device.

The object of the present invention is to render self-playing organs of this type more completely automatic through the provision 30 of an automatic means governed by the tracker range and music-sheet for controlling the actuating mechanisms of the several adjustable combination stop actions at the proper times; and a further object of the 35 invention is to provide, in instruments of this character, a manually controlled means whereby the said automatic control of the actuating mechanisms of the adjustable combination stop actions may itself be rendered operative or idle, according to the 40 wish of the player of the instrument, so that the latter may employ either the manual control or the automatic control of the adjustable combination stop actions, as desired. 45

To these ends the invention, in its broadest aspect, resides in the provision, in a self-playing organ having the usual tracker range and perforated music-sheet and one or 50 more adjustable combination stop actions, of means controlled from one or more additional or auxiliary ducts leading from the tracker range and corresponding additional or auxiliary perforations in the music-sheet

for controlling the actuating mechanism of 55 one or more adjustable combination stop actions in proper order or sequence; and the invention further resides in a manually controlled mechanism for throwing on or off such automatic control, leaving it to the 60 option of the performer to employ either the automatic control or the usual manual control.

In the accompanying drawings I have presented a conventional illustration of a 65 mechanism in which my invention may be embodied; Figure 1 being a top plan view, in horizontal section through the tracker range and its containing box, Fig. 2 an elevation in section through the several interconnected and coöperating devices shown in Fig. 1; and Fig. 3 being a detail fragmentary front elevation of the tracker range and music-sheet.

Both Figs. 1 and 2 are in part diagrammatic and do not attempt to show the exact relative positions occupied by the coöperating mechanisms or groups of devices which, in actual practice, will be widely varied according to the space conditions and 70 limitations of each installation.

Describing first those parts of a self-playing organ which are old and known, and to which my present improvement is applied, and with which it most intimately coöperates, 5 designates the tracker range, 6 the perforated music record sheet, 7 and 8 the receiving and delivery spools, respectively, of the music-sheet, and 9 the containing box or housing having a sliding glass front 85 10, within which box a suitable wind pressure of several ounces is maintained when the box is closed and a music-sheet has been put in operative relation to the tracker range. 90

At 11 are shown some of the usual draw-stops, the pulling out of which, through the individual stop actions controlled thereby, places different sets of pipes or reeds into communication with the main wind-chest of 100 the instrument, as usual in this class of instruments; and 12 designates the adjustable combination draw-stops pertaining to the adjustable combination stop actions, the drawing out of which serves to set selected 105 combinations of stops. The adjustable combination stop action (of which two are herein indicated) is a known action and com-

2

prises essentially a series of slides 13 connected by levers 14 to the rods of the respective draw-stops 11, said slides 13 carrying pivoted double-ended trips 15 that are adapted to be set to positions favorable for effecting the drawing out of previously selected draw-stops 11 through mechanism hereinafter mentioned, by means of depressible channel-shaped followers 16 that extend transversely over the series of slides 13 and are normally upheld by springs 17. Each of the followers 16 (of which there is one for each combination stop action) is depressed by a pivoted cam 18 overlying the same, said cam being actuated by the pulling out of one of the draw-stops 12 which is connected to the pivot shaft of the cam by an arm 19 and is normally held in retracted position by a spring 19a. The slides 13 are actuated in both directions (according to the positions occupied by the trips 15 carried thereby) by a mechanism comprising a pair of pivoted wipers 20 and 21, the latter of which has an upwardly extending arm 22 connected by a link 23 to the upwardly extending arm of a bell-crank 24. The wipers 20 and 21 are caused to swing simultaneously toward or away from each other through the agency of a connecting link 25 pivotally connected to the wipers 20 and 21 below and above their respective pivots. Each draw-stop 11 is provided with its own slide 13, and this latter is provided with as many pivoted trips 15 as there are adjustable combination stop actions in the instrument; each of the adjustable combination draw-stops 12 actuating one of the trip-setting followers 16.

Describing now the mechanism for selectively actuating the adjustable combination stop actions last described, the bell-cranks 24 are connected by links 26 to individual levers 27; and from the opposite ends of these latter depend thrust rods 28 each normally urged outwardly by a spring 29 into engagement with the movable side of a pressure-actuated device herein shown as a small pneumatic 30. The lower end of each rod, 28, when forced inwardly by the expansion of its pneumatic 30, directly overlies a horizontal lifter-bar 31 that is common to the several rods 28 and the several combination stop actions operated through said rods 28. The lifter-bar 31 is engaged by one arm of a bell-crank lever 32, the other arm of which is connected by a link 33 with another bell-crank lever 34, the opposite arm of which latter is engaged by a stirrup 35 on the upper side of the bellows 36 of a pneumatic motor 37. This motor has supply and exhaust passages 38 and 39, respectively, that are controlled by valves 40 and 41, respectively, said valves being connected by a rod or stem 42 so as to operate simultaneously, the closing of the one effecting

the opening of the other, and vice versa. At one end of the motor casing is a chamber 43 to which wind is continuously admitted through a supply pipe 44 tapping one side of the said chamber. Within said chamber 70 is located a pneumatic 45, the movable side of which is connected to the supply valve 40 of the motor by a link 46. It will be noted that the area of the movable side of the pneumatic 45 is greater than the area of the valve 40, and, consequently, when the pneumatic 45 is deflated, the valve 40 is opened, and the motor is energized. However, the motor is normally maintained idle through the agency of a mechanism which admits 80 pressure to the pneumatic 45 that balances the pressure on the outer surface of the movable side of the pneumatic, as herein-after explained.

Each of the pneumatics 30 communicates 85 by a pipe 47 with a wind-box 48, the pipe 47 leading into a vertical passage 49 which communicates at its upper end with the wind chamber 50 and at its lower end with an exhaust passage 51 leading to the atmosphere. Controlling the passage 49 is a valve mechanism comprising valves 52 and 53 on a valve stem 54, the valve 52 controlling the communication between the wind chamber 50 and the pipe 47, and the valve 53 controlling the communication between the pipe 47 and the atmosphere. The upper end of the valve stem 54 is connected to a diaphragm motor 55 having an area greater than either of the valves 52 and 53. 100 The diaphragm 55 is actuated to close valve 52 and open valve 53 by pressure admitted to the upper side of the said motor through a pipe 56 that communicates with a controller box designated as a whole by 57. The 105 pipe 56 leads into a horizontal passage 58 in said controller box, one end of which communicates with the atmosphere and the other end of which leads into a wind chamber 59. The ends of the passage 58 are guarded by valves 60 and 61, respectively, fast on a common valve stem 62, the arrangement being such that when one of the valves is closed the other is opened, and vice versa; and the outer end of the valve stem 62 is connected to one arm of a lever 63, to the opposite end of which lever is connected a manually operable knob 64. The valves 60 and 61 are normally maintained in the positions shown by a spring 65.

Referring now to the mechanism through which the motor is normally maintained idle by keeping the supply valve 40 closed and the exhaust valve 41 open, 66 designates another wind box that is suitably valved to control the communication of pressure to the pneumatic 45 of the main motor. The wind chamber of the box 66 has a passage 67 leading therefrom to the atmosphere, the upper and lower ends of said passage being 130

guarded by alternately acting valves 68 and 69 on a common valve stem 70; and communicating with the passage 67 between the upper and lower ends thereof is a pipe 71 that leads into the pneumatic 45 of the main motor. The valves 68 and 69 are normally in the positions shown, being maintained in such position by a spring 70^a that is of sufficient force to oppose the pressure from the wind box on the upper side of valve 69. It will thus be seen that in the normal position of the parts the pressure from the wind chamber of the box 66 passing through pipes 71 and expanding the pneumatic 45 will 10 normally maintain the supply valve 40 of the main motor closed, and hence will maintain the motor in idle or inactive condition. The action of this mechanism which maintains the main motor idle is, however, interrupted when one of the combination stop actions is to be actuated; and this is accomplished through the agency of the pneumatic 30 which, in its expanding movement to force the push-rod 28 into operative relation to the lifter-bar 31, at the same time, through a bell-crank 72, closes valve 68 and opens valve 69, thus venting pipe 71 to the atmosphere, and permitting the pressure in the chamber 43 of the main motor to open the valve 40, close valve 41, and expand the bellows 36 of the motor.

The operation of the mechanism thus far described may be briefly stated as follows. Any stop or desired combination of stops 11 is first drawn, the combination is then set by drawing out one of the stops 12, and the previously drawn stop or stops 11 are then pushed in (excepting such stop or stops as it may be desired to use in the next or a 20 succeeding combination). An additional stop or combination of stops 11, if desired, is then drawn, that combination set by drawing another of the stops 12, and the stop or stops 11 thus drawn pushed back; and so on 25 until all the desired combinations have been set, the number of such combinations being limited, of course, by the number of adjustable combination stop actions on the instrument. When the first combination is to be 30 brought into action, the operator presses inwardly the knot 64 that pertains to that combination. The chamber 59 is supplied with pressure (as hereinafter explained) and this cuts off the supply of pressure from 35 the chamber 59 to the pipe 56 by closing the valve 61, and permits the pipe 56 to vent to the atmosphere through the outer uncovered end of the passage 58. This relieves the pressure on the upper side of the diaphragm 40 motor 55, so that the pressure in the wind chamber 50, acting on the underside of said diaphragm motor, raises the valves 52 and 53. This admits pressure from the wind chamber 50 to the pipe 47 and thence to the 55 pneumatic 30, the movable side of which

latter shifts the appropriate rod 28 to a position directly over the lifter-bar 31. The same movement of the pneumatic 30, acting through the bell-crank 72, draws the valve 68 to its seat and opens the valve 69, thus 70 venting the pneumatic 45 through its supply tube 71 to the atmosphere. Thereupon the pressure in the chamber 43 supplied through pipe 44 opens the valve 40 and closes the valve 41, and enters and expands the motor 75 bellows 36, which latter, through the described connections, raises the lifter-bar 31 and thus actuates the combination stop action pertaining to the first combination. Precisely the same series of operations occur when the second knob 64 is manually actuated to bring into action the second combination of stops previously set up, and so on; it being noted that the same operation of the wipers which draws out the stops of 80 any combination draws inwardly, or returns to idle position, the stop or stops of the previous combination.

Describing now my present improvement and its co-operative relation to the mechanisms already set forth, I provide in the tracker range, and preferably at one or both ends of the latter, one or more auxiliary ducts, depending upon the number of adjustable combination stop actions on the instrument, such as those indicated at 73. These passages, which are controlled by suitably located holes or slots 6^a in the music-sheet 6, communicate through pipes 74, with ducts 75 formed in the lower side of a pair 100 of wind-boxes 76. In each of the latter is a diaphragm motor 77 communicating with the duct 75 and actuating a T-valve 78, which latter controls the communication of a pipe 79 with the wind chamber 80 of the 105 wind-box and with a vent passage 81 formed in the wind-box. The duct 75 is provided at one end with the usual bleed-screw 82 to vent the pipe 74 when the auxiliary ducts 73 of the tracker range are closed by the paper 110 music-sheet. The pipe 79 extends from the wind-box 76 into the chamber 59 of the manual control.

From the foregoing it will be seen that when one of the auxiliary apertures 6^a of 115 the music-sheet registers with one of the auxiliary ducts 73 of the tracker range, pressure from the box 9 will pass through pipes 74, activate the diaphragm motor 77, cut off communication of the wind-chamber 80 with pipe 79 and vent the latter pipe to the atmosphere. Since the valve 61 is normally open, this vents also the pipe 56, and causes the actuation of the combination stop action in the manner already described.

In order that this automatic mechanism for drawing the stop combinations may be cut out when the player desires to employ only the manual control, I interpose in the pipe 74 a pneumatically operated valve 120

mechanism, as follows: 83 designates each of a pair of valve casings provided with ducts 84 and 85 with which the interrupted sections of the pipe 74 communicate, both of 5 said ducts leading into a common valve chamber 86 in which is a T-valve 87 actuated by a diaphragm motor 88 and controlling the communication between the ducts 84 and 85, which latter constitute, essentially, portions of the duct or conduit formed by the pipe 74. In the casing 83 and communicating with the diaphragm motor 88 is a duct 89, with which communicates a pipe 90 leading from a wind-box 91. 10 The pipe 90 leads laterally into a passage 92, one end of which communicates with the wind chamber 93 and the other end of which communicates with the atmosphere through a passage 94. Controlling communication 15 of the pipe 90 with the wind-chamber and the exhaust passage 94 are a pair of valves 95 and 96 on a common valve stem 97. Connected to said valve stem is a rod 98 on the outer end of which is a manually operable 20 knob 99; and a centrally pivoted lever 100 is connected at one end of the rod 98 and at its opposite end is connected to another manually operable knob 101. With these parts in the position shown in Fig. 2, the pressure 25 from wind chamber 93 is cut off from pipe 90, and consequently the valve 87 is opened and pipe 74 is unobstructed, and the parts are in correct position for the operation of the automatic control of the adjustable combination stop actions. When, however, 30 knob 99 is pushed inwardly, pressure from the chamber 93 acting through passage 92, pipe 90, and duct 89, operates the diaphragm motor 88, closing the valve 87, and thus preventing the passage of pressure 35 through pipe 74 to the diaphragm motor 77. This, obviously, leaves the mechanism in correct condition to be operated through the manual control from the knobs 64, without 40 any interference from the automatic control. 45

It will thus be seen that my invention renders more completely automatic than has heretofore been possible the performance of self-playing organs which are equipped with 50 adjustable combination stop actions. In preferred practice, the several stop combinations used at different points in a given musical production are printed on the back of the music-record sheet, preferably at the 55 initial end thereof, so that the performer, before positioning the roll in the instrument, may readily draw and set the several stop combinations as indicated on the back of the sheet; and thereupon, having positioned the 60 roll in the instrument, he need only start the instrument in operation, and the several stop combinations will be successively brought into and drawn out of action at the appropriate times through the mechanism 65 of the present invention. In case, however,

the performer prefers to introduce the several combinations of stops at points or periods of his own selection, he may do this manually by operating the manual knob 64, having first pressed inwardly the "off" knob 70 99, which cuts out the automatic control of the present invention; or he may draw out individual stop or stops 11 manually.

I am aware that it has heretofore been proposed to effect automatically, through 75 mechanism controlled from the tracker range, the drawing of individual stops and even of fixed combinations of stops; but, so far as I am aware, my present invention is the first to provide for the automatic control from the tracker range and music-sheet of adjustable combination stop actions; and hence, realizing that this may be performed by a great variety of specifically different instrumentalities, I do not limit the present 80 85 invention to the particular means herein shown and described for this purpose, except to the extent clearly indicated in specific claims.

I claim:

1. In a self-playing instrument of the character described, the combination with a tracker range and perforated music-sheet, of a combination stop action, mechanism for actuating the latter, and automatic 90 means controlled by the tracker range and music-sheet for controlling said actuating mechanism.

2. In a self-playing instrument of the character described, the combination with a 100 tracker range and perforated music-sheet, of a combination stop action, mechanism for actuating the latter, manually operable means for controlling said actuating mechanism, automatic means controlled by the tracker range and music-sheet for controlling said actuating mechanism, and manually operable means for throwing into and out of commission said automatic controlling means.

3. In a self-playing instrument of the character described, the combination with a tracker-range having an auxiliary duct and a music-sheet having a coöperating auxiliary aperture, of a combination stop action, 115 a pneumatic motor and connections therefrom to said stop action for actuating the latter, and means set in action by pressure admitted through said auxiliary aperture and duct for admitting fluid pressure to said motor.

4. In a self-playing instrument of the character described, the combination with a tracker range having an auxiliary duct and a music-sheet having a coöperating auxiliary aperture, of a combination stop action, 125 a pneumatic motor and connections therefrom to said stop action for actuating the latter, means normally maintaining said motor idle, and means set in action by pres- 130

sure admitted through said auxiliary aperture and duct for interrupting the action of said last named means.

5. In a self-playing instrument of the character described, the combination with a tracker range having an auxiliary duct and a music-sheet having a coöperating auxiliary aperture, of a combination stop action, a pneumatic motor and connections there-
10 from to said stop action for actuating the latter, a pipe leading from said auxiliary duct, a normally open valve in said pipe, means set in action by pressure admitted through said auxiliary aperture, duct and
15 pipe for admitting fluid pressure to said motor, a diaphragm motor for closing the valve in said pipe, and manually operated means controlling the admission of pressure to said diaphragm motor.
20 6. In a self-playing instrument of the character described, the combination with a tracker range having an auxiliary duct and a music-sheet having a coöperating auxiliary aperture, of a combination stop action, a pneumatic motor and connections there-

from to said stop action for actuating the latter, means normally maintaining said motor-idle, pressure-actuated means for interrupting the action of said last named means, a valve mechanism controlling said pressure-
30 actuated means, a diaphragm motor for actuating said valve mechanism, a wind box and pipe leading therefrom to said diaphragm motor, a valve in said wind box controlling the communication of said pipe with the lat-
35 ter and with the atmosphere, a diaphragm motor controlling said valve and adapted, when actuated, to vent said pipe to the atmosphere, a pipe leading from said auxiliary duct of the tracker-range to said last
40 named diaphragm motor, a normally open valve in said last named pipe, a diaphragm motor for closing said last named valve, and manually operated means controlling the admission of pressure to said last-named
45 diaphragm motor.
